PUNCHING MECHANISM

Application filed February 4, 1929. Serial No. 337,182.

This invention relates to mechanism of the type employed in connection with punching or similar operations upon metal, the main object being the provision of a new and novel 5 means for removably securing a punch, die button, or similar article in place in a press.

Another object is to provide means for removably securing a punch or like object in place in a press whereby it may be replaced 10 without interfering with other punches positioned in the press.

Another object is to provide means for removably securing a punch or like article in place comprising a supporting or retainer 15 block adapted to be secured to a press and enclosing a screw-threaded member adapted to maintain a punch or like article in operative position when operatively associated therewith.

20 Another object is to provide, in combination with a press, a retainer member or block adapted to be rigidly secured to the press and enclosing therein a rotatable nut held against axial movement and adapted to have threaded engagement with a punch or other 25 member, means being provided for rotating the nut to engage or disengage the punch without disturbing the retainer block.

Another object is to provide means for 30 curing a punch or other article in place upon a press comprising a retainer block adapted to be rigidly secured to the press, a rotatable nut member secured against axial movement by the retainer block, a punch or other article 35 being guided in the block and having a threaded part adapted to be received by the nut, and a shoulder through which the punching or other effort is adapted to be transmitted to the nut, the nut being adapted 40 to transmit such effort to the head or table of the press and being operable from a point exterior to the retainer block for controlling its relation with the punch or other member.

Another object is to provide a means for 45 removably securing a punch or other article in a press comprising a retainer block adapted to be rigidly secured to a press part, a rotatable nut secured against axial movement by the retainer block, and a punch or other member guided in the retainer block

and having a threaded portion adapted for engagement with the nut, the nut being provided with teeth on its outer surface engageable, without removal of the retainer block, by means for controlling the rotatable position of the nut. 55

A further object is to provide means for locking the above described nut against inadvertent movement.

The above being among the objects of the present invention, the same consists in certain novel features of construction and combinations of parts to be hereinafter described with reference to the accompanying drawings, and then claimed, having the above 65 and other objects in view.

In the accompanying drawings which illustrate a suitable embodiment of the present invention, and in which like numerals refer to like parts throughout the several different views,—

Fig. 1 is a more-or-less diagrammatic fragmentary sectional view showing a punch and die operatively positioned in a press.

Fig. 2 is an enlarged partially broken fragmentary sectional view showing the means for securing the punch in position.

Fig. 3 is a plan view taken on line 3—3 of Fig. 1, and showing the nut wrench in operative position relative to the nut.

Fig. 4 is a fragmentary vertical sectional view showing a modification of the construction shown in Fig. 1.

Fig. 5 is a perspective view of the nut wrench. 85

Fig. 6 is a more-or-less diagrammatic fragmentary vertical sectional view illustrating the manner of inserting and removing the punch and die button shown in Fig. 1, the punch and die button being shown in partially inserted position.

In the formation of sheet metal parts requiring a plurality of holes to be punched therein, it is common practice to arrange the punching mechanism to punch as many holes as possible in one operation. A single punch and a single die part, commonly known as a button, is provided for each hole to be punched. If these punches or buttons are not removable from the punch press inde- 95 100

pendent of each other, a great deal of time is lost when it becomes necessary to replace one of such parts.

When such punches become dull, it requires a relatively great force to strip the article being punched from the punch, and for this reason it is imperative that the punch be secured in place so that there is no possibility of its being pulled out when the work is being stripped from it. In order to guard against such pulling out of the punch it is conventional practice to form a flange on the punch which is received in the retainer block for the punch and which necessitates removal of the retainer block in order to replace the punch. There is, to my knowledge, one construction now on the market in which the punch may be removed without removal of the retainer block, but this construction is relatively expensive to produce. The present invention provides a construction in which the punch or other part which may require replacement in a press operation, may be secured in place and be removed without disturbing the retaining member, and this in a simple and economical manner.

Referring to Fig. 1, I show by the numeral 10 what may be considered as the movable head of a punch press, and at 11 what may be considered as the table. A retainer block 12 is secured to the head 10 by screws such as 13, a plurality of which are of course employed, and the block 12 is located accurately with respect to the head 10 by dowels such as 14. The retainer block 12 has formed therein a vertical opening 15 in which the shank 16 of the punch 17 is adapted to be received and guided. The opening 15 extends upwardly through the retainer 12 and opens at its upper end into an enlarged concentric recess 18 which opens onto the upper face of the retainer block 12 where it is normally closed by the lower face of the head 10.

Within the recess 18 is positioned a nut member 19 of substantially the same diameter as the recess 18 so as to be freely rotatable and guided therein, and of such a thickness as to be retained against axial movement in the recess 18. The shank 16 of the punch 17 is provided at its upper end with a stud 20 adapted for threaded engagement with the nut 19. A shoulder 21 of material size is provided at the upper end of the shank 16 for bearing against the lower face of the nut 19, and the stud 20 is slightly less in length than the thickness of the nut member 19 so that the force exerted on the punch 17 in the act of punching is transmitted through the shoulder 21 to the nut 19 and through the nut 19 to the head 10. The nut member 19 is of hardened construction as is the shank 16 of the punch 17, so that the nut 19 acts as a follower block for transmitting the punching effort to a substantial area of the head 10.

The exterior of the nut 19 is formed with

gear teeth 22, and an opening 23 parallel to the axis of the punch 17 is provided through the retainer block 12 and intersects the edge of the recess 18. This opening is adapted to receive a wrench, such as is indicated in Fig. 5, having a shank 24 and handle portion 25, the free end of the shank 24 being formed to provide gear teeth 29 thereon. The opening 23 is so disposed relative to the nut 19 that when the end 29 of the wrench is inserted into the opening 23, the gear teeth 29 mesh with the gear teeth 22 on the nut 19, and thus act as a pinion in mesh with the gear teeth of the nut.

The punch itself is prevented from relative rotation in the opening 15 by means of a key 26 which is received in cooperating keyways 27 and 28 in the retainer block 12 and shank 16. Where the punch is of irregular shape, instead of circular as shown, the key 26 further acts to maintain the punch in proper punching relation with respect to the die.

In operation, when it is desired to insert a punch such as 17 in the retainer block 12, the shank 16 is inserted into the opening 15 and the stud 20 is pressed against the nut 19. The end 29 of the wrench is inserted in the opening 23 and is placed in meshing relationship with the gear teeth 22, and the wrench is then rotated so as to rotate the nut in the required direction to cause it to thread onto the stud 20 in the manner indicated in Fig. 6, thus drawing the punch up into place with the shoulder 21 abutting against the nut 19. The wrench is then removed and a stud member such as 30 is preferably threaded into the opening 23 until its pointed end 31 engages between two of the adjacent teeth 22 so as to lock the nut member 19 against inadvertent rotation. The removal of the punch from the block 12, of course, involves the reversal of these operations, but it will be observed that in the removal of the punch from the retainer block 12 upon counter-rotation of the nut 19, the punch is forced downwardly away from the nut. This is of advantage as is indicated in Fig. 6, in that the stripper plate 32 which is secured to the head 10 by the screw members 33 and is urged toward its lowest position by spring means 34, does not need to be sprung up against the pressure of the springs 34 in order to expose the lower end of the punch 17 to a gripping means as in the constructions now on the market.

The die button 40 which is centrally apertured as at 41 for reception of the punch 17, and against which the material 42 being worked upon rests during the punching operation, may be secured in place in a similar manner, that is, its lower end is reduced in diameter as at 43 and is threaded, and the opening 44 in the retainer block 45 opens into an enlarged recess 46 on the lower face of

the block 45 and in which the nut member 47 is rotatably retained against axial movement, the member 47 being provided with external gear teeth which are engageable by the end 29 of the wrench when inserted through the opening 48 in order to control its rotatable position. A locking member such as 49 similar to the member 30 may be provided for locking the nut member 47 against inadvertent movement. The die button 40 is, of course, provided with a key 50 for preventing rotation thereof in the retainer member 45.

It is at times necessary, due to the peculiar configuration of the article being punched, to position the punch at an appreciable distance from the head 10. The conventional method of doing this, even in the case of the removable construction now on the market, is to space the retainer block from the head 10 by a separate spacer member. This is not satisfactory due to the fact that the spacer introduces an extra joint at which a "shake" is liable to occur, and furthermore, because of the added member which must be brought into accurate alignment with the button, it is difficult to maintain the punch and button in absolute alignment. This may be readily overcome in the present invention by modifying the construction as shown in Fig. 4. As shown in that figure, a retainer block 55 of any required thickness or depth may be employed and secured directly to the head 10. The recess 18 is made of the required depth so that a standard length of punch 17 may be placed therein and be exposed the required amount below the block 55. The same nut 19 previously described is inserted in the recess 18 and a plug member, such as 56, of a length sufficient to fill the remaining depth of the recess 18 is inserted in the recess 18 between the nut 19 and the lower face of the head 10. The opening 23 and key 26 are, of course, provided as in the previously described construction. The plug member 56, in this case, transmits the punching effort from the nut 19 to the head 10.

Although I have described the present invention in connection with a punch and die such as are employed for punching sheet metal parts such as 42, it will be apparent that the construction may be modified for use in connection with drawing dies or other like tools, and I desire it to be understood that my invention is not limited to the specific tools shown in the drawings.

It will also be apparent that the particular form of gearing shown to operate the nut member 19 may be modified without affecting the present invention, and likewise the reversal of parts may be effected without materially altering the intent or result of the invention involved.

These and other formal changes may be made in the specific embodiment of the in-

vention described without departing from the spirit or substance of the broad invention, the scope of which is commensurate with the appended claims.

What I claim is:

1. In a device of the type described, in combination, a retainer block having a tool receiving opening therein, said opening being enlarged at one end to form a recess concentric therewith, a member rotatably received in said recess, said block formed with a second opening leading to said recess, and means receivable in said second opening co-operable with said member to control the rotatable position thereof in said recess, said member having threads adapted for engagement with co-operable threads on a tool received in the first mentioned opening. 70

2. In a press, in combination with a supporting surface thereof, a retainer block rigidly secured thereto, said block having an opening therein, a metal working member received and guided in said opening, a rotatable nut retained by said block, a stud on said member, and means co-operable with said nut 80 without disturbing said retainer block for controlling the rotatable position of said nut whereby to cause it to engage or disengage said stud. 85

3. In a press, in combination with a supporting surface thereof, a retainer block rigidly secured thereto, said retainer block being provided with an opening for the reception of a metal working tool, a rotatable member retained by said retainer block, a metal working tool received in said opening, co-operable screw threads on said metal working tool and said rotatable member, and means for causing rotation of said rotatable member without disturbing the relation of said retainer block in respect to said surface. 95

4. In a press, in combination, a block adapted for securement to a face of said press, said block being provided with a tool receiving opening therethrough leading to said face, said opening being enlarged adjacent said face to form a recess, a rotatable nut in said recess confined against axial movement, said block being provided with a second opening opening into said recess from a normally exposed face of said block, and means insertable into said second opening for controlling the rotatable position of said nut. 100

5. In a press, in combination, a block adapted for securement to a face of said press, 110 said block being provided with a tool receiving opening therethrough leading to said face, said opening being enlarged adjacent said face to form a recess, a rotatable nut in said recess confined against axial movement, said block being provided with a second opening opening into said recess from a normally exposed face of said block, gear teeth formed on said nut, and means insertable into said second opening for operatively engaging said 115 120 125 130

gear teeth to control the rotatable position of said nut.

6. In a press, in combination, a block adapted for securement to a face of said press, 5 said block being provided with a tool receiving opening therethrough leading to said face, said opening being enlarged adjacent said face to form a recess, a rotatable nut in said recess confined against axial movement, 10 said block being provided with a second opening opening into said recess from a normally exposed face of said block, gear teeth formed on said nut, and means insertable into said second opening for operatively engaging said gear teeth to control the rotatable position of said nut, said means comprising a wrench the end of which is formed to simulate a pinion adapted to mesh with said teeth on said nut.

7. In combination with a face of a press, a block rigidly secured thereto, said block being provided with an opening therethrough opening onto said face, said opening being enlarged adjacent said face, a member having a threaded surface rotatable in said recess in concentric relationship with respect to said opening and confined against axial movement, a metal working tool non-rotatably but slidably received in and guided by said 20 opening, said tool having a threaded surface cooperable with the first mentioned threaded surface, and a removable wrench insertable into said recess from a normally exposed face of said block for controlling the rotatable position of said member whereby to control the relation between said member and said tool.

8. In combination with a face of a press, a block rigidly secured thereto, said block being provided with an opening therethrough opening onto said face, said opening being enlarged adjacent said face, a member having a threaded surface rotatable in said recess in concentric relationship with respect to said opening and confined against axial movement, a metal working tool non-rotatably but slidably received in and guided by said opening, said tool having a threaded surface cooperable with the first mentioned threaded surface, cooperating shoulders on 45 said member and said tool for transmitting the operating force from said tool to said member independently of said threaded surfaces, and a removable wrench insertable into said recess from a normally exposed face of 55 said block for controlling the rotatable position of said member whereby to control the relation between said member and said tool.

9. In combination with a face of a press, a retainer block rigidly secured thereto having 60 an opening extending therethrough and opening onto said face, a member retained against axial movement between said block and said face in alignment with said opening, said member being apertured axially of said 65 opening, a tool received in and guided by said

opening, said tool having an end received in said aperture and locked against axial movement by said member, said block being provided with an opening leading from a normally exposed face thereof to adjacent said member, and means insertable through said opening engageable with said member to move it out of engageable relation with said end whereby to permit withdrawal of said tool from said block.

10. In combination with a face of a press, a retainer block rigidly secured thereto having an opening extending therethrough and opening onto said face, a member retained against axial movement between said block and said face in alignment with said opening, said member being apertured in alignment with said opening, a tool received in and guided by said opening, said tool having a reduced end portion received in said aperture and locked against axial movement by said member, said block being provided with an opening leading from a normally exposed face thereof to adjacent said member, and means insertable through said opening engageable with said member to move it out of engageable relation with said tool whereby to permit withdrawal of said tool from said block, said second opening being normally closed by a plug provided with a part adapted to engage said member and lock it against inadvertent movement.
